UNITED STATES PATENT OFFICE.

JAMES H. KNOLL, OF READING, PENNSYLVANIA.

DRIVE MECHANISM FOR WASHING-MACHINES.

1,174,075.

Specification of Letters Patent.

Patented Mar. 7, 1916.

Application filed July 13, 1914, Serial No. 850,686. Renewed September 24, 1915. Serial No. 52,537.

To all whom it may concern:

Be it known that I, JAMES H. KNOLL, a citizen of the United States, residing at Reading, in the county of Berks and State 5 of Pennsylvania, have invented a new and useful Drive Mechanism for Washing-Machines, of which the following is a specification.

This invention relates to drive mechanism 10 for washing machines, one of the objects of the invention being to provide power mechanism whereby motion may be transmitted from a motor to either or both the agitator of the washer and a wringer combined with 15 the washer, according to the will of the operator.

A further object is to provide in connection with a washer, a wringer mounted to swing horizontally so as to be used in connection 20 with any one of three tubs or containers, the drive mechanism being constantly in condition to actuate the wringer in any of the positions to which it may be adjusted, it being possible either to drive 25 the wringer forward or backward or to maintain the rollers of the wringer stationary.

A further object is to provide means whereby the agitator can always be stopped 30 and locked in the same position, it being possible to quickly detach the drive mechanism from the agitator when it is desired to open the lid of the washer or when it is desired to remove the tub for any purpose.

With the foregoing and other objects in view which will appear as the description proceeds, the invention resides in the combination and arrangement of parts and in the details of construction hereinafter described 35 and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is an elevation of a washing machine having the present improvements combined therewith, the 50 wringer being shown extended parallel with one side of the stand of the washer. Fig. 2 is an enlarged plan view of the structure shown in Fig. 1. Fig. 3 is an enlarged front elevation of the drive mechanism, the agitator being removed. Fig. 4 is a side elevation 55 of the structure shown in Fig. 3. Fig. 5 is a view partly in section and partly in elevation of the means provided for detachably connecting the agitator to the drive mechanism.

Referring to the figures by characters of reference, 1 designates the top of a stand, the same being supported by legs 2 which are suitably braced. A motor has been indicated generally at 3 and can be in the form 60 of an electric motor, a water motor, a spring motor or the like. This stand is designed to support the container 4 of a washing machine and also to support a tub, not shown, for receiving fabrics after they have been 65 removed from the container 4 and the water pressed therefrom.

Mounted on the top 1 of the stand adjacent the center thereof is a cross plate 5 from which depend hangers 6 and 7. A 70 transverse shaft 8 is journaled in these hangers and has a pulley 9 secured to it, this pulley being designed to receive motion, through a belt 10, from a pulley 11 driven by the motor 3. The hanger 7 is in the 75 form of a frame and has a standard 12 provided with a tubular head 13, this standard extending up to and constituting a support 80 for the swinging frame 14 of the wringer structure. An upwardly extending shaft 15 is journaled in the hanger 7 and in the 85 tubular head 13 and extends upwardly from said head through an eye 16 extending from the lower portion of the frame 14 and through a yoke 17 secured to and extending 90 from the upstanding end portion 18 of the frame 14. Thus it will be seen that the shaft 15 constitutes a pivot on which the frame 14 is free to swing in a horizontal 95 plane. Head 13 has a disk-like portion 19 provided with notches 20 and a dog 21 is pivotally connected to the eye 16 and is adapted to be seated in any one of the notches 20, thus to hold the frame 14 against swinging movement relative to the standard 100 12. It is designed to provide two notches in the disk 19 so that the frame 14 can be secured in either one of two positions, to wit, the frame can be extended transversely above the top 1 between the container 4 and 105 a tub mounted on said top and can be ex-

tended above and parallel with one side of the top, as shown in Figs. 1 and 2. Any suitable form of wringer, indicated generally at 22 is adapted to be secured upon the frame 14, this wringer having one of its rollers provided with a trunnion 23 extending toward shaft 15 and provided with a bevel gear 24. This trunnion 23 is journaled in the yoke 17 hereinbefore referred to and the bevel gear 24 is arranged between opposed upper and lower bevel gears 25 and 26 which are loosely mounted on the shaft 15 and within the yoke 17. A clutch 27 is feathered on the shaft 15 and interposed between gears 25 and 26, and any suitable means, such as a lever 28 fulcrumed on the yoke 17, can be provided for shifting clutch 27 into engagement with either of the gears 25 and 26, thus to couple said gear to the shaft 15. When the clutch is in an intermediate position, both of the gears 25 and 26 are disengaged and, consequently, shaft 15 can rotate freely within them. For the purpose of bracing the frame 14, a lug 29 is extended from the standard 12 and is pivotally engaged by the lower end of a brace rod 30, the upper end of this rod being connected to the frame 14.

A gear 31 is loosely mounted on the lower portion of the shaft 15 and has a clutch member 32 designed to be engaged by another clutch member 33 which is feathered on the shaft 15. This last named clutch member is adapted to be shifted by means of a lever 34 and, when the clutch member 33 is moved upwardly, it will become disengaged from the clutch member 32, thus permitting rotation of gear 31 independently of shaft 15 whereas, when the clutch member 33 is shifted downwardly, gear 31 will be coupled to the shaft 15.

Journaled within the hanger 7 is a short vertical shaft 35 to which is secured a gear 36 constantly meshing with a small gear 37 secured to the shaft 8. The shaft 35 has a small gear 38 fixedly connected thereto, this gear constantly meshing with the gear 31 and having a clutch member 39. Another vertical shaft 40 is journaled in the hanger 7 and in the top 1, this shaft 40 alining with the shaft 35 and being provided, at its upper end, with a crank arm 41 while slidably mounted on its lower end portion is a clutch member 42, this clutch member being feathered or otherwise held to the shaft 40 so as to rotate therewith. Said clutch member has an annular flange 43 from the lower face of which extends a V-shaped cam 44. In the upper face of the flange 43 is formed a notch 45 and, depending from the upper portion of the hanger 7 is a lug 46 adapted, under certain conditions, to extend into the notch 45. An actuating lever 47 is fulcrumed upon the hanger 7 and has a lug 48

movable therewith and adapted to be 65 shifted into and out of the path of the cam 44.

Journalized in a suitable bearing 49 provided on the top 1 and also in another bearing 50 carried by the standard 12 is a vertical shaft 51 provided, adjacent the top 1, with a crank arm 52 somewhat larger than the crank arm 41 but working in the same plane therewith. The two crank arms 41 and 52 are connected by a pitman 53 so that, when the crank arm 41 is rotated, an oscillating movement will be imparted to the crank arm 52.

Shaft 51 extends to a point above the container 4 and is provided, at its upper 80 end, with a head 54 having a longitudinal channel 55 in the top thereof adjacent one side while depending from the head and under the channel are ears 56. A yoke 57 is pivotally connected to the ears 56 and 85 carries a clamping screw 58. Channel 55 is adapted to receive a bar 59 and, by moving the yoke 57 to position so as to overhang this bar and by then adjusting the screw 58 against the bar, said bar will be caused to 90 wedge tightly within the channel 55. However, by releasing screw 58, yoke 57 can be swung outwardly from above the bar 59 and said bar lifted readily out of the channel 55.

Ears 60 extend from the ends of the bar 59 and have links 61 pivotally connected to them, these links being also pivotally connected to ears 62 formed at the ends of a head 63, this last named head 100 being secured at its center upon the upstanding shaft 64 of the agitator and which shaft is mounted for rotation in a bearing 65 mounted on the top of the container 4 at the center thereof. The two heads 59 and 105 63, and the links 61 form a parallelogram so that, by the oscillation of head 59, a corresponding oscillation of the head 63 is produced.

Assuming that the clutch members 23 and 110 32 are out of engagement with each other and that the clutch member 42 is lifted out of engagement with clutch member 39, shaft 8, which can be rotated continuously, will continuously actuate the shaft 35, motion 115 being transmitted to said shaft 35 through the gears 37 and 36. Motion will also be transmitted from gear 38 to gear 31 which, in turn, will rotate loosely on the shaft 15. When clutch member 42 is out of engagement with the clutch member 39, it is held against rotation by the lug 46 projecting into the notch 45, cam 44 at this time bearing downwardly on the elevating lug 48. As soon as lever 47 is moved downwardly, 125 the clutch member 42 will gravitate into engagement with clutch member 39, thus coupling shaft 40 to shaft 35 and causing

the crank arm 41 to rotate. Consequently crank arm 52 will be oscillated, and head 54 will be moved back and forth so as to produce a corresponding movement of the 5 head 63 and of the agitator within the tub or container 4. As soon as lever 47 is moved upwardly, the lug 48 is brought into the path of the cam 44, thus causing the cam to ride upwardly on the lug 48 and the notch 10 45 to receive the fixed lug 46. Consequently shaft 40 will be brought to a stop, it being understood that the agitator and the crank arms will always bear the same relation to each other when the mechanism is stopped. 15 Consequently there is no danger of the parts coming to a dead center when starting of the mechanism would be difficult.

When it is desired to actuate the wringer when the same is in either of the positions 20 heretofore described, lever 34 is shifted so as to bring the two clutch members 32 and 33 into engagement with each other, thus coupling gear 31 to shaft 15. By then actuating lever 28, either of the gears 25 and 26 25 can be placed in mesh with gear 24, thus causing the rollers of the wringer to feed in either of two directions desired.

By positioning the tub or container 4 as shown and by placing another tub on the 30 top 1 and a third tub at one side of the stand, the wringer can first be brought to position across the frame and between the tub 4 and the other tub on the stand so that, as the fabrics are removed from the tub 4, 35 they can be passed through the wringer into the other tub on the stand. The wringer can then be shifted to the position shown in Figs. 1 and 2 of the drawings after which the fabrics contained in the tub on the stand 40 can be passed through the wringer into the third tub. If preferred, after passing the fabrics from tub 4 into the other tub on the stand, the wringer mechanism can be reversed so as to drive the rollers in the opposite 45 direction whereupon the fabrics can be passed back through the wringer into the tub 4.

It will be seen that by means of the mechanism described, the wringer can be operated independently of the agitator and the agitator can be operated independently of the wringer or, if preferred, both the agitator and the wringer can be operated simultaneously.

It has already been pointed out that the 55 top of the tub 4 can be raised by detaching the bar 59 from the head 54, the detachment of the parts being easily effected, as heretofore described.

What is claimed is:—

1. The combination with a shaft, a crank carried thereby, and mechanism driven by the shaft, of alining shafts, means for actuating one of the alining shafts, a crank car-

ried by the other one of the alining shafts, 65 a connection between the cranks and coöperating therewith to rock the first named shaft, coöperating clutch members for holding the alining shafts normally coupled together, a lifting element, means upon one of the clutch 70 members and coöperating with the lifting element for disengaging the clutch members during the rotation of the alining shafts, and means coöperating with said clutch member for stopping the actuation of the 75 cranks when brought to predetermined positions relative to each other.

2. The combination with a shaft, operating mechanism actuated by the shaft, of a crank movable with the shaft, alining shafts, 80 a crank movable with one of the alining shafts, a connection between said cranks and coöperating therewith for rocking the shaft during the rotation of one of the cranks, coöperating clutch members normally coupling together the alining shafts, a cam upon one of the clutch members, means under the control of an operator and shiftable into the path of the cam for coöperating 85 with said cam to uncouple the clutch members, and means for holding the crank arms in predetermined positions relative to each other immediately subsequent to the uncoupling of the alining shafts.

3. The combination with alining shafts, 95 means for rotating one of the shafts, a crank carried by the other shaft, and means operated by the crank for oscillating a driven member, of coöperating clutch members upon the shafts, a lifting element under the 100 control of an operator, a cam revoluble with one of the clutch members and movable into engagement with the lifting element during the rotation of the shaft to shift one of the clutch members out of engagement with the 105 other clutch member, and means coöperating with said shiftable clutch member for stopping the rotation of the crank when brought to a predetermined position.

4. The combination with alining shafts, 110 means for rotating one of the shafts, a crank carried by the other shaft, and means operated by the crank for oscillating a driven member, of coöperating clutch members upon the shafts, a lifting element under the 115 control of an operator, a cam revoluble with one of the clutch members and movable into engagement with the lifting element during the rotation of the shaft to shift one of the clutch members out of engagement with the 120 other clutch member, and means coöperating with said shiftable clutch member for stopping the rotation of the crank when brought to a predetermined position, said means including a fixed lug, there being a notch in 125 the movable clutch member for the reception of the lug when said clutch member is shifted by its cam.

5. The combination with a shaft, of a head fixedly connected thereto and having a channel in one face, a bar detachably seated in the channel, a yoke pivotally connected to the head and movable to position to overhang the bar, means carried by the yoke for binding the bar within the channel, and driving means upon the bar.

In testimony that I claim the foregoing as my own, I have hereto affixed my signature in the presence of two witnesses.

JAMES H. KNOLL.
